UNITED STATES PATENT OFFICE

LOUIE BORTKEWICZ, OF RACOON, PENNSYLVANIA

BIT-FORGING MACHINE

Application filed May 23, 1930. Serial No. 455,005.

My invention relates to a bit-forging machine; a machine, that is to say, for forming the bits or cutting tools which are employed in coal-mining machinery. Such coal-mining machinery is well known in the art, but it may be well to remark that each machine of the type to which I refer includes a plurality of pointed cutting tools which, upon operation of the machine, are caused to cut away coal from its solid stratum in the mine. Manifestly, the cutting tools, or, as they are called in the field, the cutter bits are subject to severe service, and frequently must be renewed. As a matter of fact, cutter bits which in service have been rendered inefficient are re-pointed; each bit is repeatedly re-pointed until the body of the bit is decreased to such extent that it can no longer be adequately secured in the coal-cutting machine. In addition to the utility in forming new cutter bits the machine of my invention finds use in the sharpening or re-pointing of dull bits.

In my co-pending application Serial No. 382,214, filed July 30, 1929, which became Patent No. 1,818,601, dated August 11, 1931, I disclose a forging machine which is particularly effective to the end in view. The machine includes an anvil to which preheated bit blanks (or preheated bits to be re-pointed, for that matter) are fed. Co-operating with the anvil are two movable dies, which dies or forging heads are alternately brought to forging position against the anvil, and so, upon a sequence of such alternate movements of the dies, a cutter bit is formed. The dies of the machine do their forging under the reactionary forces of springs, and I point out in the above mentioned application the advantages of spring-operated dies. That is, spring-operated dies have been found to deliver a forging blow which is closely akin to a blow delivered by a hand hammer—a blow which is instrumental in improving rather than spoiling the grain structure of the steel bit. For purposes of safety, as well as for simplicity of structure, the instrumentalities for operating the forging dies are organized below the bed of the machine. This machine has been successfully operated, and has been found advantageous in the particulars set forth, and

my present invention has to do with certain refinements which will presently be described.

It often happens that the stock of which a new bit is to be forged (or the shank of an old bit which is to be re-pointed) is bent, and one important refinement of this invention concerns a blank-straightening device which is associated with the novel blank feeding means of my improved machine. Other valuable improvements and refinements in the structure of the machine are described in the following specification.

In the accompanying drawings Fig. I is a view in plan of the improved machine; Fig. II is a view of the machine in side elevation; Fig. III is a view in cross-section, taken on the plane III—III of Fig. I, showing to larger scale the blank-straightening device; Fig. IV is a view in vertical section, taken on the plane IV—IV of Fig. II, illustrating in detail the blank-feeding portion of the machine; and Fig. V is a view of the top of the plunger which is employed in the feeding device of the machine, and there is shown in association with the plunger the ejector for effecting the discharge of finished bits from the machine. It is to be understood that the drawings are diagrammatic, and that only such portions of the machine as are considered to be essential to a clear understanding of its operation and structure are indicated.

The machine comprises a bed, to which bed the reference numeral 1 is immediately applied, and frame members 2 support such bed. A feeding device, indicated generally by the reference numeral 3, is adapted to present blanks through an opening 4 in the bed of the machine to an anvil 5, and two dies or heads 6 and 7 are reciprocated and brought alternately into forging position upon the anvil to form a cutter bit (or, as mentioned above, to re-point a bit which in use has become dull). The anvil 5 includes two faces one of which is formed complementary to the forging face 8 of head 6, and the other one of which anvil faces is formed complementary to the forging face 9 of head 7. Together the anvil faces and the forging faces of these heads are adapted, when the

heads are operated, to build the required point B on the cutter bit A.

As before noted, it is desirable that the heads (6 and 7) shall strike bit-forming blows which are similar to those delivered by a hand hammer. To this end resilient means are organized in the machine to effect the movement of the heads 6 and 7 into forging position upon the anvil 5. In the illustrated embodiment of the invention, I attach an arm 16 to the head 7. The head is slideable in a guide 17. This arm 16 is pivotally mounted between the bracket 18 of the machine, and by means of the pin and groove connection 19 the angular oscillation of the arm 16 is transmitted to the head to effect its reciprocation in the guide 17. Fixed to the arm 16 at one end, and to a stationary portion of the machine at the other end, is a spring 20. Means are provided to rotate positively the arm 16 against the resistance of spring 20, and after so moving the arm against such resistance the said means are adapted to release the arm to the forces of the distended spring. Manifestly, in the illustrated machine the spring will effect the movement of the head 7 into forging position against anvil 5.

The means for effecting such positive movement and the release of the arm 16 advantageously comprise a cam 21 which is affixed to a counter shaft 22. This counter shaft is geared at 23 to the drive shaft 24 of the machine, and the drive shaft is conveniently equipped with a belt pulley 25 and a clutch 26 for controlling the rotation of said shafts. As may be seen in Fig. IV, the cam 21 has an indented surface 21a, and rotation of the cam in a clockwise direction will periodically effect the release of the end 16a of the arm 16, and thereby permit the spring 20 to operate the forging head, as described. After such release of the arm 16, further rotation of the shaft 22 and cam 21 brings the cam to such position that its face portion 21b presses against the end 16a of the arm, and continued rotation of the cam effects the return of the arm and head to its initial position, for the delivery of another forging blow. In this position, due to the fact that cam surface 21c bears against the end 16a of the arm, the arm and head are maintained for an interval of time sufficient to permit the unobstructed operation of the forging head 6.

The head 6 slides in a guide 30, and, as indicated in Fig. I, is adapted to strike a bit blank which is in position upon the anvil a forming blow. To provide the desired point on bit blank A the forming blows of head 6 are directed at an angle of 90 degrees to the line of movement of the head 7. An arm 33 is pivoted to a standard 34, and is secured to the head 6 by means of the pin and groove connection 35. A spring 36 is secured to the arm 33 and to a convenient stationary por-

tion of the machine, similar to the manner in which the spring 20 is secured to the arm 16. By means of the helical cam 37 the end 33a of the arm 33 is released to the force of the expanded spring 36, and, of course, movement of the head 6 into forging position is thereby effected. Due to its particular structure cam 37 is adapted to effect a return of arm 33 to its initial position (Fig. II), and there it retains the arm until the head 7 has performed. In the matter of simplicity of structure, it will be noted that the cams (21, 37) are of such form as to permit both of them to be affixed to the shaft 22. Such unitary mounting of the cams is advantageous, because it permits the cams to be adjusted on a single shaft, and insures a positive synchronization of the alternately moving heads 6 and 7.

It is desirable to move the heads 6 and 7 angularly downward upon the anvil. The troublesome inertia of the moving parts of the machine seems to be more readily overcome, and the forging operation of the machine is improved, when the dies or heads are reciprocated upon an incline instead of in a vertical or horizontal path. Between the removal from the anvil of a finished cutter bit and the insertion of a new bit blank, an interval of time elapses, and in this interval of time the forging heads tend to beat violently upon the anvil. (It is, of course, assumed that the machine functions continuously while each batch of heated blanks is being forged). Such beating of the anvil is objectionable—obviously so,—and to overcome the objection I provide cushioning means of particularly efficient and simplified structure. These cushioning means (both heads being similarly cushioned) comprise a member 60 of resilient material (such as spring steel), which member 60 is rigidly secured to the body of the forging head. For the greater part of the travel of the head the member 60 moves freely within a groove 70 which is provided for it in the guide associated with the head. When, however, the head reaches such position in its forging stroke that the forging face of the head is about to strike the anvil 5, the member 60 comes against a stationary shoulder 80 in the groove 70. Consequently, the force of the impact of the head on the anvil is damped: indeed, by appropriately disposing the shoulder 80, the forging head may be prevented from striking the head; furthermore, the force with which the forging head strikes a bit blank on the anvil may in like manner be regulated.

I have stated that before feeding a blank or a dull bit to the anvil for forging, it is desirable and quite often necessary to straighten the body portion of such blank or bit. To effect the straightening of the blanks, I provide in the feeding device 3 an oscillating die 42, pivotally mounted on a pin 43. It is of advantage to so locate the blank-straighten-

ing means within the feeding device; this is for the reason that the heated blank to be forged need be handled only once to obtain the truing of its body, the feeding of it to the anvil, the forging of its cutting point, and its removal in finished form from the machine. Referring to Figs. III and IV, it may be seen that the feeding device 3 includes a chute 41 for passage of a blank into the machine. Adjacent the mouth 40 of this chute the pivotally mounted die 42 is located, and an arm 44 having the eccentric head 45 is oscillated to effect the oscillation of the die 42, as indicated by the dotted line in Fig. III. The arm 44 is pivotally secured on a pin 46, and, as is manifest in the drawings, the eccentric head 45 causes with a wiper cam action the oscillation of disc 42, that is, when the arm 44 is vibrated about pin 46. Convenient means to effect the vibration or oscillation of arm 44 include a lever 47 which is pivotally secured at 48 to the frame 2 of the machine. The outer end of the lever 47 carries a rod 49, and the upper end of this rod is in engagement with the terminus of arm 44. The inner end of lever 47 rides a wiper cam 50, which wiper cam is geared to a moving element of the machine for rotation. Through such linkage the oscillation of die 42 is conveniently obtained.

In the operation of the machine a heated blank A (Fig. III) is dropped into the mouth 40 of the feeding device, and the powerfully vibrating die 42 with a rapid succession of movements squeezes the body of the blank against the wall 41a of the chute 41. So, while passing into the chute 41, the blank A is straightened. When it is freed from the die 42 the blank A slides down chute 41, across opening 51, and lands point up upon the plunger 52. By means of convenient connections (not shown) the plunger 52 is elevated, bringing the blank A up through passage 54 to suitable position for forging on the anvil 5 (see Fig. IV). When the forging heads 6 and 7 have sufficiently operated to build the desired point on the blank, the plunger is lowered, bringing with it the finished cutter bit. While the plunger is on its way downward an ejector 53 is caused to move from the full line to the dotted line position of Fig. IV; and, as may be realized from the showing in Fig. V, the ejector and the plunger are of such complementary structure that the ejector may be so moved, without interfering with the movement of the plunger. The ejector, however, does intercept the cutter bit in its downward movement; that is to say, the ejector in its declining position is instrumental in causing the finished bit A, as the plunger lowers, to slide outwardly through opening 51 and away from the machine. It will be understood that the ejector 53 is maintained in its full-lined position when the plunger 52 is moving upward to

present a bit blank to the anvil. Accordingly, the passage 54 is unrestricted during the feeding of a bit blank. When, however, the bit blank has been forged, and the plunger is moved downward, the ejector 53 is swung to its dotted line position. In such dotted line position the ejector lies athwart the passage 54; due to the complimentary shape of the ejector and plunger (see Fig. V) the plunger moves freely past the ejector in its downward movement. The finished bit resting on end upon the plunger is engaged by the upper faces of the ejector, and thereby is caused, as the plunger lowers away from the ejector, to slide to the right (Fig. IV) and down passage 51. The means for operating the ejector, as well as the means for operating the plunger are not shown in the drawings, inasmuch as their provision is a matter for the ordinary engineer.

A more detailed description of the above-mentioned parts will be seen in my co-pending application for Letters Patent Serial No. 601,315, filed March 26, 1932.

I claim:

1. In combination with a blank-feeding device including a chute, a pivotally mounted die in the wall of said chute, and means for continuously oscillating said die, whereby a blank, upon entering the device, moves by gravity past said oscillating die and is straightened.

2. In combination with a bit-forging machine including a forging head and operating means for powerfully reciprocating such forging head, a blank-feeding device, which feeding device comprises a chute arranged at an angle to the horizontal, and a pivotally mounted die associated with said chute, together with connections from said operating means to said die for effecting the oscillation of said die about its pivotal mounting, whereby a blank, upon entering the device, moves by gravity past said oscillating die and is straightened.

In testimony whereof I have hereunto set my hand.

LOUIE BORTKEWICZ.
